Anderson Miller and Thos Lawes. Citizens of the United States
Improvement in the Machine for Hulling
Setters 3 bottom side.
Patent 3 Date of the Patent 27 Oct 1835
No. 664 } Certificate Atty Gen Oct 31st 1835

The Schedule referred to in these Settled Patent and making part
of the same containing a Description in the words of the said Anderson
Miller & Thos Lawes themselves of their improvement in the
machine for hulling Cotton seed.

To all to whom these Presents shall come
Be it known that we Anderson Miller of the County of Wash-
ington in the State of Mississippi and Thomas Lawes of the County
of Jefferson in the State of Kentucky have invented a new & use-
ful improvement in the cotton seed Hulling Machine of Messrs.
Tollett & Smith of Petersburg in the State of Virginia and the
following is a full and exact description of the construction
and operation of said machine as improved by us. By for the
purpose of a clear & definite description a drawing of the machine
as improved by us is herewith annexed; the frame of the Hulling
Machine is made of cast iron, the sides, together with bolts in a neat
and substantial manner. All the journals turn in brass boxes
the cog wheel on the hulling stone & slack wheel is made of cast
iron, they are represented in brass on the model the slack wheel
& easily, is for the purpose of throwing it out of gear at plea-
sure. The feed box which stands over the hulling stones is to ex-
tend up to the floor, above where the seed is let into the upper
end of the box and falls to the revolving wheel in a box with
iron teeth. The eccentric roller parallel with the above wheel can
be turned round which makes the space larger or smaller, and re-
gulates the feed; there is an index wheel, on eccentric roller, with
a pin to hold it fast, when in the right position thus the feed is re-
gulated without any difficulty, passes through between the stones

to the double middle which rests on three iron rods and shaken by a
bank. The sand passes down close by the fan & the hull is blown
off
